UNITED STATES PATENT OFFICE.

WILLIAM D. HARPER, OF SAN ANTONIO, TEXAS.

VEHICLE-BODY SUSPENSION.

1,366,796.

Specification of Letters Patent. Patented Jan. 25, 1921.

Application filed May 3, 1920. Serial No. 378,445.

To all whom it may concern:

Be it known that I, WILLIAM D. HARPER, a citizen of the United States, and a resident of the city of San Antonio, in the county of Bexar and State of Texas, have invented new and Improved Vehicle-Body Suspensions, of which the following is a full, clear, and exact description.

This invention relates to improvements in vehicle body suspensions, an object of the invention being to provide an improved construction and arrangement of parts which will permit a limited swing in all directions of the body on its supporting chassis.

15 A further object is to provide improved coupling means connecting the body and chassis which will take up shocks and jars, and prevent transmission of the same to the body.

20 A further object is to improve upon the construction disclosed in my pending application for patent filed June 20, 1919, and given Serial Number 305,525.

With these and other objects in view, the invention consists in certain novel features of construction, and combinations and arrangements of parts as will be more fully hereinafter described and pointed out in the claims.

30 In the accompanying drawings:

Figure 1 is a view in end elevation illustrating my improvements.

Fig. 2 is a broken view in side elevation.

35 Fig. 3 is an enlarged view in section on the line 3—3 of Fig. 1.

Fig. 4 is an enlarged view in section on the line 4—4 of Fig. 2.

1, 1 represents the longitudinal bars of a chassis across which tubular transverse positioned supporting members 2 are located and secured on the bars 1 by means of U-bolts 3.

45 U-bolts 3 are provided at both sides of the bars 1 and at their upper ends straddle the tubes 2. The lower end of the U-bolts 3 are projected through perforated plates 5 below the bars 1, and secured in place by means of nuts 6, thereby securely clamping the tubes 2 on the bars 1, so that said tubes 50 form, in effect, fixed parts of the chassis.

4 represents the body, or platform thereof, supported on longitudinal bars 7, and the latter secured across transversely positioned bars 8.

55 The bars 8 are arranged in pairs, as

shown clearly in Fig. 3, and have depending blocks 9 at their ends.

Tubes 10 are secured to the bearing blocks 9 by means of screws 14 projected through the tubes 10 and screwed into the blocks 9; or any other form of securing means may be employed.

It will be noted, particularly by reference to Fig. 4 that the tubes 2 project beyond the bars 1, and that the tubes 10 are located under, and at right angles to the projecting ends of tube 2.

Twisted links 11, constituting hangers are supported on the tubes 2 and in turn support the tubes 10 and the vehicle body 4.

The tubes 2 are of appreciably greater diameter than tubes 10 and the links or hangers 11 at their ends are of appreciably greater diameter than the tubes, so that said links are permitted a limited swaying or rocking movement on the said tubes, thus preventing sliding movement.

U-shaped rivets or staples 12 and 13 are secured in the tubes 2 and 10 respectively, and at their ends are positioned around the links 11 to hold the parts in proper relative position.

By reason of the construction above described, the body 1 is supported entirely at its four corners, by the links or hangers 11 and the tubes 2 and 10 which are coupled by said hangers, not only give a maximum strength and durability to the structure, but permit a swaying motion to permit the load to ride easily on the chassis, and absorb a large portion of the shocks and jars that would otherwise be transmitted to the body and load thereon.

While I have described the body as having my improved mounting at the four corners, it is obvious that any number of such connections might be employed and located as may be desired.

Various slight changes might be made in the general form and arrangement of the parts described without departing from my invention, and hence I do not limit myself to the precise details set forth, but consider myself at liberty to make such slight changes and alterations, as fairly fall within the spirit and scope of the appended claims.

I claim:

1. The combination with a vehicle chassis, and a body above the same, of transversely positioned members supported on the chassis.

and projecting at their ends beyond the side bars of the chassis, longitudinal members supporting the body and located below the outer ends of the first-mentioned members, and hangers supported on the first-mentioned members and supporting the last-mentioned members.

5. 2. The combination with a chassis and a body, of transversely positioned tubes on the chassis, longitudinally positioned tubes secured at the corners of the body, twisted links supported at one end on the first-mentioned tubes and having a rocking motion thereon, and said last-mentioned tubes mounted in the lower ends of the links and having rocking motion therein.

10. 3. The combination with a chassis and a body, of transversely positioned tubes on

the chassis, longitudinally positioned tubes secured at the corners of the body, twisted 20 links supported at one end on the first-mentioned tubes and having a rocking motion thereon, said last-mentioned tubes mounted in the lower ends of the links, and 25 U-shaped devices secured in the tubes and engaging the links.

4. The combination with a chassis, a body, pairs of transverse bars on the body, and blocks on the lower faces of the bars, of tubes connecting the blocks and secured 30 thereto, transverse tubes secured on the chassis and projecting beyond the sides of the latter, and link hangers on the last-mentioned tubes and supporting the first-mentioned tubes.

WILLIAM D. HARPER.
